UNITED STATES PATENT OFFICE.

FREDERICK J. JACKSON, OF TARRYTOWN, AND WILLIAM H. WRIGHT, OF SAUGERTIES, NEW YORK.

WASH-BOILER.

SPECIFICATION forming part of Letters Patent No. 240,518, dated April 26, 1881.

Application filed February 12, 1880.

To all whom it may concern:

Be it known that we, FREDERICK J. JACKSON, of Tarrytown, Westchester county, State of New York, and WILLIAM H. WRIGHT, of 5 Saugerties, in Ulster county, in said State, have invented certain new and useful Improvements in Wash-Boilers, of which the following is a specification.

The object of our invention is to construct, 10 the bottom of the boiler in an improved manner, whereby great strength, durability, and efficiency, as well as cheapness of construction, will be attained, while embodying a formation specially suited to produce an energetic fountain-action on the well-known principle of fountain-boilers.

To this end the main feature of our invention may be stated to consist in constructing, 20 a wash-boiler with a cast metal (preferably cast-iron) bottom, joined to sheet-metal sides by preference. In forming this bottom with a downward depression to enter the fire-chamber of the stove, and covering this depression within the boiler, thus forming a fountain-chamber directly in the boiler-bottom itself, 25 to one end of which the cooler water of the boiler may be admitted, while the water, becoming highly heated in this chamber, may be discharged through a nozzle in a foaming stream over the top of the clothes to again 30 return to the fountain-chamber in the well-known manner of fountain-boilers.

Our invention also consists in the special form of this depression or fountain-chamber, 35 in the boiler-bottom, and in several other details of the boiler, as hereinafter fully set forth.

Figure 1 of the drawings annexed presents a plan view of my improved boiler with the cover removed. Fig. 2 is an inverted plan of 40 the bottom thereof. Fig. 3 is a vertical diagonal section on line α α of Fig. 1, the cover applied, and a guard-rack adapted to overlie the clothes shown in place. Fig. 4 is a plan view of the guard-rack removed.

45 The boiler, as illustrated, is made in the usual oblong shape, with rounded ends; but it may be made in other shapes when desired. The bottom of the boiler is preferably formed of cast-iron, which is both galvanized and tinned, while the sides are preferably made of

the usual sheet metal joined to the edges of the cast bottom.

The cast-iron bottom A may be formed with the usual depression to enter the fire-chamber of the stove; but in case of a fountain-boiler, 55 the depression is preferably made in a special form. We, however, prefer to adopt the novel form illustrated, which is that of a broad corrugation of sinuous or flat S shape, as seen best in Fig. 2, which provides greater heating- 60 surface, and may be used either in the ordinary boiler or in the fountain-boiler.

The cast-metal bottom A is also preferably formed, as shown in Fig. 3, with a raised rabbed edge, c, over which the bottom edge of the 65 sheet-metal sides is turned, and soldered both inside and out. This construction renders the union of the bottom and sides very secure, and raises and protects the joint from contact with the stove-top, whereby it is protected from excessive heat and abrasion, as will be readily 70 understood.

It may now be readily perceived that in constructing the bottom of the boiler of cast-iron we secure the important advantages of cheapness, strength, durability, and ease of handling. The bottom being cast in one piece, of 75 inexpensive metal, is thus much cheaper than the usual sheet-metal bottoms formed by dies; and, moreover, this cast bottom is much better able to resist wear, and is not liable to be injured by abrasions or rough usage, or to be punctured by contact with sharp objects; and hence the boiler can be slid on or off the stove without requiring to be bodily lifted on or off, 80 so that it may thus be handled with much greater ease. On the contrary, the ordinary sheet-metal bottoms are, as is well known, 85 easily injured or punctured by rough abrasions or contacts, and require careful handling in lifting on or off the stove.

We prefer, as will be obvious, to construct the boiler-bottom of cast-iron, on account of its strength and cheapness; but it may also be made of cast-brass or similar metal, which will 95 secure the same advantages above set forth.

Now, in a fountain-boiler, we cover the cavity of the depression or depressions d d within the boiler by a plate or plates, e e' e'', level with the general face of the bottom, thus form- 100

ing a confined boiling or fountain chamber directly in and forming part of the bottom itself. The cover of this fountain-chamber is preferably made of cast metal, in three pieces 5 or plates, $e e' e''$, one to each groove or depression, which are soldered in place over the cavities, as shown in Figs. 1 and 3. An inlet is formed at one end of this cavity or chamber, as shown at f , by a rise or overbend in 10 the plate e , which inlet is guarded by short bars $g g$, cast on the bottom, and forming a strainer, to prevent the entrance of any fabric therein. The outlet of the cavity is at the opposite end, through the nozzle h , which rises 15 from a bulge on the plate e'' over the discharging end of the cavity, and is bent at the top to discharge the foaming stream of water which boils out of the cavity or fountain-chamber over the top of the clothes in the usual 20 manner of wash-boiler fountains.

It will be seen from Figs. 1, 2, and 3 that this fountain-chamber is directly in the bottom of the boiler, and that it is of sinuous form or direction, and tapers from end to end, widening 25 toward the discharge. The water, therefore, which enters the chamber becomes exposed to the direct heat of the fire, and taking a sinuous passage through the chamber becomes very quickly and highly heated there- 30 in, and as it finds an easier passage toward the discharge, where the passage widens, the boiling stream thus rushes out of the discharge-nozzle in an uninterrupted current of great volume and steadiness, which is dis- 35 charged over and descends through the clothes with an energetic washing action. This construction, as may be inferred, causes the water to become more highly heated than usual in fountain-boilers, and insures a more certain 40 and voluminous flow, so that the improved boiler is practically found to wash and bleach clothes in a superior manner with the use of ordinary suds, and without the necessity of rubbing, thus forming a simple and efficient 45 washing-machine.

We prefer to construct the fountain-chamber in the boiler-bottom not only of sinuous continuation, but also curved in cross-section, each bend thus presenting a distinct surface, 50 as seen best in Figs. 2 and 3, as this provides greater heating-surface; but, if desired, the fountain-chamber may be formed by one broad flat depression, which may be divided by vertical partitions or webs cast on the bottom, 55 so as to form a sinuous passage through the same.

To properly hold the mass of clothes down in the boiler and prevent their becoming ruffled up by the strong stream from the nozzle, 60 we employ an open frame, i , of wood, (shown best in Fig. 4,) and preferably formed of two parallel longitudinal bars joined by two connecting cross-bars, which frame is supported on short lugs or shoulders $m m$, projecting 65 from the sides of the boiler, near the top, as shown in Figs. 1 and 3. These shoulders, as

shown in Fig. 3, are double, consisting of an overlying and underlying shoulder, the lower ones being longer than the upper ones, so that the ends of the cross-bars of the frame being 70 placed on the lower ones may be then slipped along under the upper ones, thus retaining the frame securely in place.

We also provide the edge of the boiler-cover with a marginal packing, of felt, rubber, or 75 other suitable material, to render the fit of the cover in the boiler steam-tight, and thus prevent the escape of steam; and we also prefer to fit the cover with spring-catches $n n$, which spring over and catch upon the bead around 80 the top edge of the boiler, thus holding the lid down securely.

We prefer, also, to attach to the boiler-cover a flexible hose, k , of canvas or rubber, terminated with a metallic thimble, which may be 85 coupled with a thimble projecting from the stove-pipe, and thus serve to conduct the steam from the boiler to the flue and prevent its objectionable escape into the apartment.

It will be readily understood that while we 90 prefer to construct the boiler-bottom of cast-iron or similar cast metal, yet it may also be formed of sheet metal in several pieces, soldered together in the described form, without departing from the described features of our 95 invention as applicable to fountain-boilers.

We do not claim herein a sunken wash-boiler bottom having a fountain-chamber within its pit or depression, and provided with a top plate having an elevated end forming an 100 inlet or inlets to said chamber, and supported by stud-pins, which form strainers at said inlets; nor a wash-boiler having a sunken bottom, with a fountain-chamber within its pit or depression, and provided with an elevated outlet 105 projecting over the marginal floor of the bottom, as we intend to claim these features in another application for patent.

What we claim as our invention is—

1. A wash-boiler having a bottom formed 110 with a broad longitudinal groove, depression, or cavity of a sinuous continuation and curved section closed by a suitable cover, and provided with an inlet at one end and an outlet at the other, substantially as and for the purpose 115 set forth.

2. A fountain wash-boiler having a bottom formed with a permanent cavity or fountain-chamber of sinuous continuation and in part integral with said bottom, substantially as 120 herein shown and described.

3. A fountain wash-boiler having at or in its bottom a fountain-chamber of sinuous continuation and of a diameter increasing from the inlet to the outlet, substantially as and for 125 the purpose herein set forth.
